UNITED STATES PATENT OFFICE.

HOWARD B. LOXTERMAN, OF PITTSBURGH, PENNSYLVANIA, ASSIGNOR TO BLAW STEEL CONSTRUCTION COMPANY, OF HOBOKEN, PENNSYLVANIA, A CORPORATION OF NEW JERSEY.

MOLD-FORM.

1,227,280.

Specification of Letters Patent. Patented May 22, 1917.

Application filed February 5, 1916. Serial No. 76,344.

To all whom it may concern:

Be it known that I, HOWARD B. LOXTERMAN, a citizen of the United States, residing at Pittsburgh, in the county of Allegheny and State of Pennsylvania, have invented certain new and useful Improvements in Mold-Forms, of which the following is a specification.

This invention relates to mold forms, and more particularly to that class of forms used in the formation of the lower segments of a concrete tunnel, and has for its principal objects, the provision of a mold form which is simple, durable and easily applied and removed, the provision of a form that may be quickly set in place and which can readily be removed to another position when the concrete has become set, the provision of a mold form wherein the frame carrying the form has telescoping engagement with the truck, whereby the form may be raised and lowered with respect to the truck, the provision of a truck for supporting the form which carries rails for a material car whereby material can be supplied at points intermediate the ends of the form, and such other advantages as may hereinafter appear. Certain embodiments of the invention are shown in the accompanying drawings, wherein—

Figure 1 is an end view of the complete mold form and truck; Fig. 2 is a side elevation of the truck and frame with the mold form removed, and Fig. 3 is an end elevation of a modified form of mold form and truck.

Referring more particularly to Figs. 1 and 2, the apparatus comprises a pair of arcuate mold forms 1 which serve to form the concrete into lower half of the tunnel walls. Concrete is poured in at the top of the mold sections at A or points farther down the mold, and the concrete deposits between the form and the earth, indicated by dotted line B.

The mold sections 1 are supported by a frame comprising a cross girder 2, the forms having sliding engagement with the ends of the girder and attached thereto by means of the pins 3 which pass through the slots 4. Each mold section 1 is built up of panels which are joined to make up sections of approximately thirty feet in length, each sec-

tion being supported by four sets of cross girders 2, see Fig. 2.

The cross girders 2 are connected by angle beams 5, and are supported by the vertical channels 6 which are bolted to the girders 2 and project downward into engagement with the truck. The truck comprises a base formed of transverse channels 7 which are supported upon truck channels 8. These channels extend longitudinally of the form, the truck wheels 9 being pivoted between them upon the shaft 10, which extends through both sets of truck channels 8. The transverse channels 7 are connected by longitudinal girders 11, between which vertical columns 12 project upwardly. These columns 12 comprise spaced channels 13 securely fastened at their lower ends to the transverse channels 7 and to the longitudinal channels 11. Side plates 14 are riveted to the webs of the channels 13 forming a rectangular space between the inner faces of the channels 13 and the plates 14.

The vertical channels 6 of the frame telescope into the columns 12 of the truck and any lateral displacement of the frame with respect to the truck is prevented. A pair of jacks 15 are mounted upon the longitudinal girders 11 at each side of the truck, and engage at their upper ends the longitudinal frame girders 16 which connect the vertical channels 6. The frame, therefore, may be raised or lowered with respect to the truck by turning the screws of the jacks.

The lower ends of the mold sections 1 are supported by means of turn buckles 17 which connect the mold sections with the truck, the inner end of the turn buckle being pivoted to clips 18 which are riveted to the vertical channels 13. By turning the buckle the lower end of the form may be raised or lowered as may be desired and adjustment of the upper end of the mold section 1 is accomplished by manipulation of the turn buckle 19, which is attached at one end to the web plate 20 and at the other end to the bracing angle 21. As there is a slot and pin engagement between the web plate 20 and the cross girder 2, the top of the mold section may be moved in or out to adjust the form into proper position.

When it is desired to place the form in po-

sition the turn buckles 17 and 19 are positioned in order to properly center the mold sections after the truck has been moved into a new position. After the concrete has been 5 filled in and has become properly set the mold sections are withdrawn from the concrete by means of the turn buckles and the frame is then elevated by means of the jack screws 15, so that the mold sections entirely 10 clear the formed concrete. While the sections are in this withdrawn position the truck carrying the frame and sections may be again advanced into a new position and another section of the tunnel formed. 15 Upon the cross channels 7 of the truck, a pair of wooden stringers 22 extend longitudinally of the form and serve to support a pair of rails 23. These rails carry a truck 24 which is filled with mixed concrete and 20 may be moved along the rails to the position best suited for unloading where the concrete is needed. The provision of a track for the concrete car mounted upon the mold form truck makes it possible to distribute 25 concrete where needed quickly and efficiently and has many advantages over the old method of supplying concrete, which necessitated carrying the concrete from the end of the mold. The open construction of this 30 mold form support, including the frame and the truck, permits of free movement in the operation of the form and the distribution of concrete.

Referring to Fig. 3, a modified form of 35 truck and frame construction is illustrated which works on a similar principle to that of the apparatus just described with the exception that the truck sections are not connected as in the previously described apparatus. The shape of the mold form is irregular, this form being adapted to produce 40 ledges or benches extending longitudinally of the tunnel. The material car in this case is not carried by the truck but is mounted 45 upon the base timbers which serve to support the rails upon which the form trucks ride.

This apparatus comprises form sections 25 and 26 which are supported upon the cross 50 channels 27 by means of the pins 28 which are slidably mounted in slots 29 cut in the webs 30, which are bolted to the extreme ends of the cross channels 27. The upper ends of the mold forms are moved in or out 55 by means of turn buckles 31 in a manner similar to the previously described apparatus, and the lower ends of the forms are moved inward by means of turn buckles 32 which are secured at one end to the lower 60 end of the mold form and at the other end to webs 33 which are secured to the vertical truck columns 34.

The truck columns 34 are built up of channels 35 in a manner similar to the apparatus 65 previously described, and receive the verti-

cal channels 36 which project downwardly from the cross channels 27 and have a telescoping engagement with the vertical columns 34. The channels 37 extend longitudinally of the mold and rigidly connect the 70 vertical channels 36. The vertical column 34, which is built up of the channels 35, is securely riveted to the longitudinal truck channels 38, which carry the truck wheels 39 between them. Jack screws 40 are 75 mounted between the longitudinal channels 37 and the truck channels 38 and are for the purpose of raising and lowering the frame which carries the mold sections relatively with respect to the truck members. It will 80 be seen that vertical adjustment of the mold sections may be readily obtained by manipulation of the jacks 40, and that the mold sections may be moved inward by means of the turn buckles 31 and 32. Therefore, the mold 85 sections may be moved vertically and laterally as desired, for adjusting the mold sections in proper position and properly centering them.

The mold sections in this apparatus comprise a pair of curved top sections 41 and 42, a pair of stepped flat sections 43 and 44, and lower curved sections 45 and 46. The curved sections 41 and 42 are connected to vertical angles 47 and 48, respectively, by means of brace plates 49 and 50, respectively, and the angles 47 and 48 are secured to the curved bottom sections 45 and 46, respectively, and serve to support them. In order to withdraw these forms from the finished 90 concrete it is necessary to move them inwardly by means of the turn buckles and then move them vertically by means of the jack screws 40, after which the form may be moved into position for forming a new 95 section of the tunnel.

The trucks are supported upon rails 51 which extend longitudinally along the bottom of the tunnel and are supported by cross timbers 52, and another pair of rails 53 extend longitudinally of the tunnel and are supported upon the cross timbers 52. These latter rails are for supporting cars for carrying the concrete. 100

It is obvious that many changes may be 115 made in the details of the construction illustrated without departing from the spirit of the invention and the invention is not limited to the specific apparatus herein illustrated and described.

What I claim is:

1. In combination, a mold form, a truck, vertical standards carried by the truck at each side thereof, a frame for supporting the mold form having downwardly extending vertical standards adapted to slidably engage the vertical standards on the truck, and means for holding the frame in various adjusted positions with respect to the truck. 125
2. In combination, a mold form, a truck, 130

vertical standards carried by the truck at each side thereof, a frame for supporting the mold form having downwardly extending vertical standards adapted to telescopically engage the vertical standards on the truck, and means whereby the frame may be moved vertically with respect to the truck.

3. In combination, a truck, a mold form, spaced hollow vertical standards carried by the truck at each side thereof, a frame for supporting the mold form having downwardly extending vertical standards adapted to telescope within the vertical standards

carried by the truck, and means whereby the frame may be vertically adjusted with respect to the truck. 15

4. In combination, a truck, a mold form, a rigid frame for supporting the mold form, and a plurality of telescoping columns having their ends rigidly connected to the truck and the frame for adjustably supporting the frame above the truck, and means whereby the frame may be adjusted vertically with respect to the truck. 20

HOWARD B. LOXTERMAN.
